Washington I. Avery
By *Chas. E. Gile* ATTY.

UNITED STATES PATENT OFFICE.

WASHINGTON I. AVERY, OF NEW YORK, N. Y.

DESIGN FOR A CAT.

SPECIFICATION forming part of Design No. 33,270, dated September 25, 1900.

Application filed August 23, 1900. Serial No. 27,857. Term of patent 7 years.

To all whom it may concern:

Be it known that I, WASHINGTON I. AVERY, a citizen of the United States, residing in the city of New York, in the county and State of New York, have invented and produced a new and original Design for a Cat, of which the following is a specification, reference being had to the accompanying drawings, forming a part thereof, and in which—

Figure 1 is a side elevation of a cat bearing and incorporating my design, and Fig. 2 an end elevation of same.

The leading feature of my design consists in the form and configuration of the cat, substantially as shown.

In the drawings, A designates the article as a whole, said article comprising the central

cylindrical body portion B and tapered end portions C, the portion B having at each end the annular groove D, and said end portions C having adjacent to their outer extremities the annular grooves E, the whole being substantially as shown.

What I claim is—

The design for a cat, substantially as shown and described.

Signed at New York, in the county and State of New York, this 22d day of August, A. D. 1900.

WASHINGTON I. AVERY.

Witnesses:

CHAS. C. GILL,
GUNDER GUNDERSON.
